UNITED STATES PATENT OFFICE

WILLIAM M. ALEXANDER, OF MONROE, NORTH CAROLINA

AEROPLANE

Application filed November 5, 1931. Serial No. 573,199.

The invention relates to aeroplanes, and has for its principal object the provision of means whereby the air displaced by the propeller and driven rearwardly is utilized to provide a lifting impulse for the plane.

A further object of the invention is the provision in an aeroplane of a body or fuselage being provided at its front end with a tubular opening in which is mounted the propeller, and providing at the rear of the tubular opening air deflectors leading to openings in the side walls of the body or fuselage and directed under the wings so that the air displaced by the propeller and driven rearwardly therefrom is discharged through the openings in the sides of the body against the wings or planes to give a lifting impulse to the aeroplane, thereby aiding the plane in taking off from the ground, and also maintaining it in flight.

The invention will be described in detail hereinafter and will be found illustrated in the accompanying drawings, in which

Figure 1 is a top plan view, partly broken away and in section of the improved aeroplane,

Figure 2 is a side view also partly broken away and in section,

Figure 3 is a transverse sectional view on a plane indicated by the line 3-3 of Figure 2,

Figure 4 is a transverse sectional view of one of the wings on a plane indicated by the line 4-4 of Figure 1, and

Figure 5 is a sectional detail on a plane indicated by the line 5-5 of Figure 1.

In the drawings similar reference characters are used to designate corresponding parts in all of the views.

As shown in the drawings, the aeroplane has its body or fuselage 1 provided with a tubular opening in its forward end in which is mounted the propeller 3 and motor 4 by means of suitable supports 5. Mounted in the tubular opening 2 and rearward of the motor and propeller is an air deflector 6 including curved walls 7 that meet on a line 8 arranged vertically in the tubular opening 2 and intermediate of the sides of the body 1, the curved walls being converged rearwardly and laterally to openings 9 in the side walls

of the body and immediately under the wings or planes 10. The openings 9, are as shown best in Figures 2 and 5 elongated longitudinally of the body of the plane, the forward end of said opening designated 9^a being wider than the rear ends 9^b and arranged in alignment with grooves 11 formed by rearwardly directed flanges 12 on the under sides of the wings, to prevent the air discharged through the openings 9 from spilling forwardly of the wings and to provide a forward thrust as well as a lifting impulse by the air displaced by the propeller and directed through the openings 9. As shown in Figure 1 the flanges 12 and grooves 11 are curved outwardly and rearwardly of the wings or planes 10, and the flanges and grooves are tapered outwardly of the wings.

In the type of plane selected for illustration there is shown a control and passenger compartment 13 mounted on top of the body or fuselage 1 and having a plurality of windows 14 arranged at the front and along the sides thereof, and a door 15 for ingress and egress. It will be understood, however, that the arrangement of the tubular opening in the front of the plane and for discharge of the air displaced by the propeller through the sides of the body of the plane and under the wings is equally applicable to planes of the type wherein the control and passenger compartments are arranged in the body of the plane including planes employing a cockpit for the aeronaut, so that the invention is not restricted to application to the type of plane selected for illustration.

It will also be apparent that the air displaced by the propeller 3 and driven rearwardly through the tubular opening 2, as well as the air caught in the opening 2 by the forward motion of the plane will be divided by the deflector 6 and driven out of the openings 9 with great force and thereby have a lifting effect on the wings or planes 10 that will materially assist the plane in taking off as well as maintaining it in flight, and as heretofore stated the air caught in the grooves 11 will provide a forward impulse to the aeroplane to aid it in its forward progress. It will also be understood that the combined

areas of the openings 9 may be equal to the area of the tubular opening 2, or the areas of said openings 9 may be increased or diminished as may be found to operate the most satisfactorily.

Also to increase the effectiveness of the blast of air under the wings or planes 10, their rear edges are provided with enlargements 10^a that are substantially triangular as shown, having one of the sides of the triangle abutting the body or fuselage 1 and their opposite angles substantially coincident with the outer ends of the grooves 11.

What is claimed is:—

- 15 1. In an aeroplane, a body having a tubular opening in its forward end, a propeller mounted in said opening and adapted to discharge air through the opening, the sides of said body having openings communicating with said tubular opening, deflectors mounted in said tubular opening and having rearwardly curved walls directed laterally to the openings in the sides of the body to deflect air through said openings, planes secured to the body above the side openings for discharge of air therefrom against the under side of the planes, and a grooved flange on the under side of each plane extending outwardly of the plane from the forward edge of each side opening.
- 20 2. In an aeroplane, a body having a tubular opening in its forward end, a propeller mounted in said opening and adapted to discharge air through the opening, the sides of said body having openings communicating with said tubular opening, deflectors mounted in said tubular opening and having rearwardly curved walls directed laterally to the openings in the sides of the body to deflect air through said openings, planes secured to the body above the side openings for discharge of air therefrom against the under side of the planes, and a grooved flange on the under side of each plane extending outwardly of the plane from the forward edge of each side opening.
- 25 3. In an aeroplane, a body having a tubular opening in its forward end, a propeller mounted in said opening and adapted to discharge air through the opening, the sides of said body having openings communicating with said tubular opening, deflectors mounted in said tubular opening and having rearwardly curved walls directed laterally to the openings in the sides of the body to deflect air through said openings, planes secured to the body above the side openings for discharge of air therefrom against the under side of the planes, and a grooved flange on the under side of each plane extending outwardly of the plane from the forward edge of each side opening, the grooved flanges adjacent to the body being under the forward edges of the planes and curving outwardly and rearwardly of the planes.
- 30 4. In testimony whereof I affix my signature.
WILLIAM M. ALEXANDER.
